UNITED STATES PATENT OFFICE.

RAYMOND F. BENNETT, OF PORTLAND, MAINE.

METHOD OF AND APPARATUS FOR FORMING TRENCHES.

Application filed January 7, 1927. Serial No. 159,675.

In forming trenches in shifting media, such as sand and particularly in sand where the tide ebbs and flows, serious difficulties are encountered due to such natural conditions. On a characteristic contract which I have recently completed, these natural factors were particularly unfavorable. The contract called for the laying of a pipe line several hundred feet long across a tidal flat where the average rise and fall of the tide was about nine feet. In addition, the topography was such that even at low water one end of the pipe line was always submerged and the gradient of the line varied considerably at different sections thereof. This not only meant that work could only be done during the average few hours of low water, but that during the flood tide the sand would be washed back in the trench and had to be cleared out again when the tide ebbed.

I saw at once that existing methods would not suffice. For example, it was not practicable simply to excavate a wide trench and use flexible pipe joint, first on account of the filling in of the trench at each tidal change, and second, on account of the expense of the flexible pipe joints. Nor could I follow the usual practice involving the driving of two spaced lines or courses of tight sheeting, excavating the earth and sand therebetween, and bracing the sheeting and completing the driving as the excavations proceeded because such a method would have required a large crew of men and inasmuch as work could only be done at low tide, the crew would have been idle too long in proportion to their actual working time.

I was therefore compelled to devise a method and structure which would be practical under the conditions which confronted me. For the purpose of this application, I have selected this particular piece of work as characteristic of the principles of my invention, but it is to be understood that such treatment is purely illustrative and in no way limiting. Generally speaking, the principles of my invention apply to the construction of any trench where simplification of procedure and lower production cost are factors. My invention is especially applicable however in the excavating of comparatively shallow trenches in runny soils such as sand, quicksand, or similar shifting media and where the excavation has to be made

in or under water, as in flats and marshes subject to tidal overflow.

Broadly, my method involves the use of a movable shield which provides an excavating chamber within which full depth excavation may be done as well as a work chamber within which the pipe or other work may be laid as the excavating proceeds, the walls of the shield serving as stays for the trench walls while the excavation is being made, and the pipe laid or other work done and the shield itself being intermittently moved ahead when the excavation within its confines is completed and used. In the particular piece of work in question, the excavating machine was mounted on a gantry which itself was located in comparatively deep water even at low tide so that the starting end of the pipe line was submerged. The initial excavating therefore was begun inside of the shield so as to allow the shield to settle vertically into position by reason of its own weight plus such additional force or weights as were necessary to insure that it be sunk to the required depth. When the excavating had been completed to full depth within the shield and also to a slight depth in advance of the shield, and before the earth had time to fill in, the shield was pulled ahead by means of a tackle and harness connected with the fixed post or "dead man" at the far end of the pipe line course, for a distance as far as it was possible to hold the side banks from caving in. The excavating machine was then drawn forwardly by means of the same harness and tackle to a position where further excavation ahead of and within the shield could be accomplished, and the operation was repeated until the entire trench had been excavated.

In the accompanying drawings I have shown my method and apparatus in connection with the particular piece of work for which it was originally designed, although it is to be understood that this treatment is illustrative and not limiting.

In the drawings:

Fig. 1 is a side elevation partly in section illustrating the practice of my invention under typical conditions.

Fig. 2 is a fragmentary plan view of Fig. 1 with the excavating machine removed to illustrate details of construction.

Fig. 3 is a side elevation of my shield.

Fig. 4 is a vertical section along the centre line of the shield.

Fig. 5 is a plan of Fig. 4, partly in horizontal section.

5 Figs. 6 and 7 are typical cross sections on the lines 6—6 and 7—7 respectively of Fig. 3, and

Fig. 8 a modification for soft mud operation.

10 In Fig. 1 the starting end of the pipe line is represented as being submerged even at low tide and the gantry and excavating apparatus are conventionally shown.

My shield comprises spaced side members 15 indicating generally at A and B between which excavation to full depth is done as indicated at D and which side members shore up the walls of the trench as it is dug. The side members are duplicates, preferably being 20 formed of planks 1 placed edgewise on top of each other, the lowermost planks resting on longitudinally extending timbers 2 which carry on their under sides angle irons 3. These angle irons form cutting edges 25 which facilitate sinking the shield when beginning operations and also assist in keeping the shield down to its proper depth when its lower edge is at or slightly below the bottom of the trench at all points and especially where 30 changes in the gradient are made.

At the forward end of the side members A and B and projecting beyond the planking 1 is a series of cutter plates 4 disposed en echelon, as appears in Figs. 3 and 4. These 35 plates facilitate the penetration of the shield through the soil when the shield is forced forwardly beyond the excavation D which it occupies. Preferably, the forward end of the shield is stepped off, as shown, so that 40 the forward cutting edges of the plates 4 are vertical or substantially vertical. Vertical disposition of these plates insures that the forward movement of the shield will be stopped by any hard obstruction encountered, rather than permitting the shield to ride up on the obstruction as would be the case if the forward cutting edges were inclined instead of vertical.

The side members A and B constituting 50 the sheeting are held in correct relation to each other by the bents C of which there may be any desired number spaced along the shield towards its rear end, and by the cross struts 5 and 6, which struts define the excavation 55 chamber D of the shield. Each bent C is composed of side posts 7 joined together at their upper ends by girders 8 and diagonally braced by braces 9 and cross struts 10, the space beneath the strut 10 being left clear 60 for pipe laying or other work which is to be done behind the strut 5 or in rear of the excavation chamber D.

The strut 5 is disposed between a pair of vertical posts 11 at either side of the shield 65 and the shield is reinforced laterally by re-

inforcing members 12, which are attached to the posts 11 above the forward ends of the planks 1 and to the forward strut 6. Between the posts 11 and the forward ends of the side members are diagonally disposed members 13 to which the side planks 1, the timbers 2 and the reinforcing members 12 are attached, and these members 13 project beyond the side planking and are fastened at their upper ends to the strut 6.

The side members A and B are spaced apart sufficiently to afford sufficient space F between them for conveniently carrying on in the trench whatever work is to be done. The outside contact surfaces of the side members A and B, above the angle-irons 3, 75 may be spaced slightly farther apart at the forward ends of the shield than at the rear end so that the shield may be more easily pulled along in the trench, the pressure of 80 the earth being thus somewhat relieved as the shield progresses because the contact surfaces tend to pull slightly away from the side earth as the shield progresses.

Inasmuch as the angle irons 3, are partly 85 or wholly submerged in the earth on the inner side, it is desirable that these angle irons should be strictly parallel to each other. This may be effected by having the outer surfaces of each angle iron 3 and timber 2 90 flush at the forward end of the shield, and offset at the rear end half the amount on each side that the woodwork is tapered. In other words, the woodwork above the angle-irons 3 is tapered, the angle-irons themselves 95 being parallel to each other.

Most of the excavating is done in the forward compartment or excavating chamber D of the shield between struts 5 and 6. Some 100 excavating is also done just ahead of the shield as indicated at E. The sides of this chamber D are shown extending somewhat above the side reinforcing pieces 12. These 105 reinforcements protect the planking against the wear and hits of the excavating bucket, and also serve to guide the same. If desired, these side pieces may be still further extended in height, so as to reach the surface of 110 the water at a higher level, and thereby form guides for the bucket, so that excavating 115 could be done in greater depths of water than would otherwise be the case.

The construction work is done in the space between the side members A and B, and back of the strut 5. This space may be 120 termed the construction chamber F.

Procedure varies according to existing 125 conditions. For example, if the trench is to be begun abruptly, as on level ground, the shield is placed in position and the excavating begun inside, so as to allow the shield to settle vertically into position by reason of its own weight or added forces or weights. Or if the slope assumed by the material will permit, a wide ditch with sloping sides may 130

be dug nearly to the required depth, and the shield deposited therein. If the trench is to be begun gradually, or to enter a bank, the shield may be put in line and the excavating 5 be done at the forward end, and the shield gradually dragged into the ground to the required depth as by the tackles 14, 14, attached to the forward end of the shield. The excavating in the general run of work is 10 to be done in the forward chamber D and just ahead of the shield. It may be done by grab bucket, operated by suitable power, or by any other method, means, or apparatus, or by hand. The excavated material may be 15 deposited at one side to be later back-filled, or taken away entirely, or deposited back of the shield as a backfill in one operation.

Assuming the shield to be placed at the depth required the routine of work, as in 20 pipe laying, would be as follows: The excavating of the earth would be done to a slight depth just ahead of the shield, as indicated at E, and to the full depth or below in the excavation chamber D, then before the earth 25 has time to run in, the shield would be moved ahead as far as possible to hold the side banks from further caving. In this manner progress along the trench would be made by alternately digging and pulling 30 the shield ahead, but the digging and moving ahead of the shield may be done simultaneously in the most unstable soils, and possibly, to greater economic advantage in all soils. The movement of the shield may 35 be accomplished by pulling it ahead, as by the tackles 14, or by forcing it ahead from behind by jacks, or by any other suitable means.

Before the shield is moved ahead, however, the trench already excavated in the 40 shield, would be utilized for the laying of pipe 15, or other work from the rear end up to a point just back of the strut 5. The shield is then moved ahead gradually until 45 a sufficient length of trench is open to allow the construction work in the same to proceed. Or the excavating ahead, the movement of the shield, and the pipe laying all might be carried on simultaneously.

50 In practice it has been found advisable to put sand bag weights in the upper part of the bents C and resting on the strut 10, to keep the rear end of the shield down, and to hold it from floating.

55 If water is present and the construction work must be carried on in the dry, damming and pumping may be necessary.

The dam at the rear end of the shield may be formed by the back fill, by a partial dia- 60 phragm in the rear end of the shield, by sand bags, or otherwise. The sides of the shield may be made to serve as side dams, and the strut 5 may be so shaped and placed as to form the dam in the front end. When 65 operating by the alternate, rather than the

continuous method, the cycle of operations would be as follows: Excavated ahead, move shield ahead, pump out trench, lay pipe, and back-fill in rear of shield or within rear end of the shield. 70

Various other modifications in method may be practiced, as for example, in the case of soft mud, as shown in Fig. 8. In such a case the beach instead of being sand S, as indicated in Fig. 1, may be mud M, as 75 indicated in Fig. 8. In operations where a pipe has to be laid or like trenching done in an ooze or fluid mud, I vary my shield structure by a timber dam as indicated by the timbers 5¹ thus making of the opening at the end of the shield as indicated at D in Figs. 80 3 and 5, a more complete pocket from which the mud can be dredged. In this case the shields are warped ahead into the soft mud 85 without any advance excavation as indicated at E in Fig. 3. On account of the softness of such mud, the shields 12 can be readily advanced and the flow of the mud held by the cross timbers 5¹.

This variant in operation is not essentially different from that heretofore described in connection with work on a sand beach or beach of other dry or only partly wet nature. In any case the bucket is operated as required in the open end between the 90 members 12, there being sufficient distance between the timber 6 and the timber or timbers 5 to give free bucket or dredge room.

What I therefore claim and desire to secure by Letters Patent is:

1. The method of forming trenches which consists in sinking a shield, in excavating within said shield, in excavating at the end of said shield, and in advancing said shield into said excavation ahead upon completion 100 of the excavation within the shield to permit work to be completed in said excavation within the shield.

2. The method of forming trenches in shifting media, which consists in sinking a shield into the media, in excavating to full depth within said shield, in excavating slightly at the end of said shield, and in advancing said shield into said excavation ahead upon completion of the excavation 105 within the shield to permit and finally work to be completed in said excavation within the shield.

3. The method of forming trenches, which consists in sinking a shield having an excavating portion and a work portion in rear of said excavating portion, in excavating within said excavating portion, in excavating at the end of said shield, and in advancing said shield into said excavation ahead upon completion of the excavation within 110 said shield to permit work to be completed in the excavation comprised within said work portion.

4. The method of forming trenches in 115

shifting media, which consists in sinking into said media a shield having an excavating portion and a work portion in rear of said excavating portion, in excavating to full depth within said excavating portion, in excavating slightly ahead of said shield, and in advancing said shield into said excavation ahead upon completion of the excavation within said shield to permit work to be completed in the excavation comprised within said work portion.

5. In apparatus for use with a trench excavator, a shield comprising spaced side members cross-connected to each other and sustained as an excavating portion and a work portion in rear of said excavating portion.

10. In apparatus for use with a trench excavator, a shield comprising spaced side members cross-connected to each other and sustained as an excavating portion and a work portion in rear of said excavating portion and having at their forward ends cutter members for facilitating the advance of the shield through the soil.

20. In apparatus for use with a trench excavator, a shield comprising spaced side members including bottom angle-irons and sheeting thereabove, said side members being cross-connected and sustained as an excavating portion and a work portion in rear of said excavating portion.

25. In apparatus for use with a trench excavator, a shield comprising spaced side members including bottom angle-irons and sheeting thereabove, said side members being cross-connected and sustained as an excavating portion and a work portion in rear of said excavating portion, and having at their 35 forward ends cutter members for facilitating the advance of the shield through the soil.

30. In apparatus for use with a trench excavator, a shield comprising spaced side members, a bent, a pair of spaced cross struts in advance of said bent, the space

between said struts constituting an excavating portion and the space between said bent and the rearward strut constituting a work portion disposed in rear of said excavating portion.

50. In apparatus for use with a trench excavator, a shield comprising spaced side members, a bent, a pair of spaced cross struts in advance of said bent, the space between said struts constituting an excavating portion and the space between said bent and the rearward strut constituting a work portion disposed in rear of said excavating portion, the forward end of the shield being longitudinally reinforced and having a cutter for facilitating the advance of the shield through the soil.

55. In apparatus for use with a trench excavator in shifting media, a shield comprising spaced side members including bottom angle irons, timbers carrying the same, and sheeting superposed on said timbers, a bent, a pair of spaced cross struts in advance of said bent the space between said struts constituting an excavating portion and 60 the space between said bent and the rearward strut constituting a work portion disposed in rear of said excavating portion.

65. In apparatus for use with a trench excavator in shifting media, a shield comprising spaced side members including bottom angle irons, timbers carrying the same, and sheeting superposed on said timbers, a bent, a pair of spaced cross struts in advance of said bent, the space between said struts constituting an excavating portion and the space between said bent and the rearward strut constituting a work portion disposed in rear of said excavating portion, the forward end of the shield being longitudinally reinforced and having a cutter for 70 facilitating the advance of the shield through the soil.

75. In testimony whereof I affix my signature.

RAYMOND F. BENNETT.
